HYDRAULIC REMOTE CONTROL
APPARATUSCharles Hyland, Wakefield, England, assignor to
Hyland Automobiles (England) Limited, Wake-
field, EnglandApplication August 7, 1942, Serial No. 454,006
In Great Britain May 23, 1941

3 Claims. (Cl. 60—54.5)

This invention relates to hydraulic remote control apparatus, the chief object being the provision of a hydraulic remote control whereby a plurality of predetermined movements at the remote or receiving end can be obtained at the discretion of the operator at the control or transmitting end. A further object is the provision of such a remote control which will automatically provide at the control or transmitting end an indication that the receiver has operated in accordance with the actuation at the control or transmitting end.

According to the invention, the hydraulic control apparatus comprises essentially a hydraulic ram at the remote or receiving end which is operatively connected to the apparatus to be actuated and which is adapted in conjunction with ports in its cylinder to function as a valve, said ports being connected by pipe lines controlled by a further or another remote valve whereby they can be selectively connected to the pressure side of a hydraulic pump, closed, or connected to the exhaust. The arrangement is such that not only can the ram be caused to make a complete full stroke in either direction, but also it can be caused to perform intermittent or partial strokes according to the predetermined positions of the cylinder ports, the length of the piston-like portion of the ram, and the setting or operation of the selector valve controlling the pipe lines to said ports. Thus the remote control apparatus is adapted to give a plurality of definite movements at the remote end at the discretion of the operator at the control end, which movements can be imparted either directly or through appropriate gearing to the apparatus or mechanism which is under control.

The desired indication of the correct operation of the ram at the remote end may be afforded by an indicator associated with the selector valve at the control end and actuated by an auxiliary hydraulic ram or piston which is positively operated by and in accordance with the displacement of the main ram. In this connection the auxiliary ram cylinder would be connected in series with the main ram cylinder and would preferably have a slightly less displacement volume than the latter so as to ensure that said auxiliary hydraulic ram or piston will always reach the end of its stroke before the main ram does so. The working fluid displaced by the main ram in completing a full stroke beyond the capacity of the auxiliary cylinder would be by-passed to exhaust through one or more appropriate non-return valves which may be associated with ports leading into the

auxiliary cylinder, and the auxiliary ram or piston may co-operate with these ports in the manner of a valve to permit the additional or excess fluid displaced by the main ram to pass through the auxiliary cylinder to exhaust by way of the control or selector valve. The indicator may comprise a pointer operated, either directly or through gearing, by the auxiliary ram or piston and working in conjunction with a scale or dial which may be engraved according to the particular purpose or apparatus to which the remote control is applied, whilst the hydraulic system may also include a maximum pressure release valve, to control the maximum pressure in the ram cylinder, and a hand operated by-pass valve on the ram cylinder to enable the ram to be moved by hand if required or in an emergency, say when the hydraulic transmission fails through any cause.

20 The remote control apparatus may be duplicated or further multiplied according to the number of elements to be separately actuated, that is to say, there may be a plurality of hydraulic rams, one for each element to be actuated, each under 25 the control of a separate selector valve, and all supplied from the same pressure pump, and where there are a plurality of selector valves these may be incorporated in a panel or valve chest at the control or transmitting end and to 30 which the pressure side of the pump is connected.

The hydraulic fluid or oil supply may be carried in a tank at a sufficient head or elevation above the ram or rams and connected preferably through a filter to the pump inlet, whilst the 35 exhaust from the selector valve or valves is returned to said tank.

In order that the invention may be clearly understood and readily carried into effect, the same will now be more fully described with reference to and by the aid of the embodiments illustrated in the accompanying drawings, wherein—

Figure 1 is a diagrammatic view of the lay-out of a remote control apparatus constructed according to the invention.

45 Figure 2 is a part sectional elevation of the hydraulic ram at the remote or receiving end of the apparatus.

Figure 3 is a part sectional elevation of the indicator.

50 Figure 4 is a similar view to Figure 1 showing the hydraulic ram at the remote or receiving end in its right hand position.

Figure 5 is a similar view to Figure 4 showing the hydraulic ram at the remote or receiving end in its intermediate position.

Figure 6 is a part sectional elevation of the selector valve.

Referring to the drawings, wherein the invention is applied to the actuation of a soot blower, the ram 1 of the hydraulic remote control is adapted to take up three predetermined positions as shown in Figures 1, 4, and 5 of the drawings corresponding to the fully retracted position of the blower nozzle (not shown), the fully projected position of said nozzle where it extends into the boiler furnace (also not shown), and the intermediate position at which nozzle rotation or oscillation commences during the forward stroke, the ram 1 being connected (but not shown) to the blower nozzle by means of rack and pinion and step-up gearing to convert the linear motion of the ram to rotary motion required for actuating the screw-operating gear of the blower nozzle.

The hydraulic fluid or oil is supplied to and returned from the ram cylinder 2 by three pipes 3, 4, 5 which connect it to a selector valve 6 of the piston type, and having three positions corresponding to those of the ram 1. The pipes 3 and 5 connect to ports 7, 8 at opposite ends of the ram cylinder and the third pipe 4 connects to an intermediate port 9 which is so located to correspond with the intermediate position of the ram 1, whilst the length of the piston-like portion 10 of the ram 1 which co-operates with said intermediate port 9 in the manner of a valve is predetermined in accordance with the partial stroke required for oscillating the blower nozzle.

The selector valve 6 has a hollow valve member 14 with an axial chamber 28 open at the upper and lower ends within the selector valve 6. At the lower end of the valve 6 is an annular port 29 open to the exhaust pipe 15 whilst a further annular port 30 connects to the pressure supply pipe 12. Further ports 31, 32, and 33 connect with the pipes 3, 4, and 5 respectively from the hydraulic ram cylinder 2 at the remote or receiving end. A through chamber 34 connects the axial chamber 28 of the hollow valve member 14 so that ports 31 and 32 and consequently pipes 3 and 4, may be connected through the chambers 33 and 28 to the exhaust pipe 15. A port 35 is provided at the upper end of the hollow valve member 14 to enable the port 33 in the selector valve 6 and its pipe 5 to be connected to exhaust 15 when the hollow valve member 14 is in its lowest position as shown in Figure 4 of the drawings. An annular port 36 on the hollow valve member 14 permits the port 33 and pipe 5 to be connected to the pressure supply pipe 12 as shown in Figure 5 of the drawings.

With this arrangement the operation of the apparatus is as follows: Starting with the selector valve in the position shown in Figure 1 of the drawings, fluid pressure is supplied through ports 36 and 33 of the selector valve member 14 and valve 6, through pipe 5 to the port 8 of the ram at the remote or receiving end. Port 32 of the valve 6 is closed with the result that the pipe 4 and its port 9 are also closed. Port 31 is open to exhaust by way of the chambers 34 and 28 in the hollow valve member 14 so that the pipe 3 and its port 7 in the ram cylinder 2 are at exhaust with the result that the piston 10 of the ram 1 is at the left hand end of the cylinder 2. By moving the selector valve into the position shown in Figure 4 of the drawings, port 8 of the ram, pipe 5 and port 33 of the valve 6 are connected to exhaust through the port 35 and cham-

ber 28 in the hollow valve member 14 and port 9 of the ram, pipe 4 and port 32 of the valve 6 are connected to exhaust through the chamber 34 in the hollow valve member 14. At the same time port 7 of the ram, pipe 3 and port 31 of the selector valve are connected to the pressure pipe 12 by way of ports 30 and 36 with the result that the piston 10 of the main ram 1 makes a complete stroke to the right hand end of the cylinder 2 into the position shown in Figure 4. In order to make the piston 10 of the ram 1 perform a partial stroke, the selector valve 6 is moved into the position shown in Figure 5 of the drawings wherein port 7 of the ram, pipe 3 and port 31 are connected to exhaust as also are port 9, pipe 4 and port 32. Port 8, pipe 5 and port 33 are connected to the pressure pipe 12 with the result that the piston 10 of the ram 1 moves to the left until it uncovers port 9 which is at exhaust and comes to rest as shown in Figure 5 of the drawings.

A partial stroke of the ram 1 may only be made when the piston 10 of the ram is at the rear end of its cylinder 2 or the position shown at Figure 4 so that a partial stroke only constitutes travel by the piston 10 from ports 8 to 9 in either direction in the ram cylinder 2.

If, however, the selector valve 6 is set to connect the intermediate port 9 to the exhaust pipe 15, the end port 8 to the pressure supply and the other end port 7 to exhaust, the ram 1 will perform a partial stroke which will be determined when said piston-like portion 10 uncovers said intermediary port 9 and thereby releases the pressure from the cylinder 2. A partial ram stroke in a reverse direction may then be effected by adjusting the selector valve 6 so as to reverse the end ports 7 and 8 connections, whilst maintaining the intermediate port 9 open to exhaust. In this way the ram may be caused to have a to-and-fro short stroke action equal to the length of the piston-like portion of the ram, in addition to the full stroke action when the intermediate port is closed and only the end ports are operative, and such short action is imparted to the blower nozzle for effecting the oscillating movement thereof. The lower end of the valve unit 14 has a port or passage 35' to the passage 28 and port 35.

The indicator comprises an auxiliary cylinder 16 which has a slightly less displacement volume than the main ram cylinder 2, and is connected in series therewith by being interposed in the pipe line 3 leading from the selector valve 6 to the end port 7 of the main cylinder 2, whilst the connections 17 and 18 to said auxiliary cylinder 16 have each associated therewith a by-pass port 19 and 20 respectively, each controlled by a non-return valve at 21 and 22. Each by-pass port 19 and 20 leads into said cylinder at such a distance from the ends 23 and 24 that it will be uncovered by the auxiliary ram or piston 25 when the latter is at that end. Thus when the main ram 1 makes a full stroke in one direction oil is supplied to one end of the main cylinder 2 and oil displaced from the main cylinder operates the indicator ram or piston 25 and causes it to make a complete stroke, the excess oil displaced beyond the capacity of the auxiliary or indicator cylinder 16 being passed through the latter by one of the valve controlled by-pass ports 19 or 20 to the selector valve 6 and thence to the exhaust 15. For a full main ram stroke in the reverse direction the pressure oil supplied through the selec-

tor valve 6 operates the auxiliary ram or piston 25 to cause it to make a full stroke and the oil displaced by the auxiliary piston or ram is forced into the main cylinder 2 to actuate the main ram 1, whilst when the auxiliary ram or piston 25 has reached the end of its full stroke it has uncovered the other valve controlled by-pass port 19 or 20 so that pressure oil passes through the auxiliary cylinder 16 to the main cylinder 2 to complete the stroke of the main ram 1.

When the main ram 1 is caused to make a partial stroke from the right hand end of the cylinder 2, the fluid oil in said cylinder 2 forward of the piston 10 is displaced due to the movement of the said piston 10 and the connecting of the pipe 3 to exhaust. The displaced fluid acts upon the piston 25 of the indicator so that the latter is moved an amount corresponding to the displacement which in turn is directly proportionate to the movement of the piston 10 of the main ram and in this manner the indicator shows that a partial stroke of the main ram has taken place. Similarly when the main ram 1 is returned to the right hand end of the cylinder, the pipe 3 as previously described is connected to the pressure supply with the pipes 4 and 5 to exhaust and the moving pressure fluid through the pipe 3 acts upon the piston 25 of the indicator to operate the latter and show that the piston 10 of the main ram 1 has moved to the right hand end of its cylinder 2.

I claim:

1. Hydraulic remote control apparatus comprising a cylinder arranged to be operatively connected to the apparatus to be actuated, said cylinder having spaced inlet and outlet ports, a reciprocating ram in said cylinder for controlling the flow of fluid into and out of said ports, said ram being selectively movable to three predetermined positions, a selector valve for controlling the position of said ram, pipes communicating the selector valve with said ports, said selector valve having a delivery passage communicating with a spaced exhaust passage, and valve means within the selector valve for controlling the flow of the fluid therefrom into and out of the cylinder so as to actuate the ram, means for operating said valve means, an auxiliary cylinder interposed between the selector valve and the ram cylinder and communicating therewith through

one of said pipes so as to be connected in series with the ram cylinder, an auxiliary piston within the auxiliary cylinder operable in accordance with the displacement of the ram, and an indicator operatively connected to said auxiliary piston for showing the correct operation of the ram.

2. A hydraulic remote control apparatus comprising a ram cylinder provided with ports at opposite ends and with an intermediate port, a reciprocating ram for controlling the flow of fluids into and out of said ports, said ram being selectively movable to three predetermined positions, a selector valve for controlling the movement of said ram, pipes communicating the selector valve with the ram cylinder through said ports, valve means within said selector valve for controlling the flow of fluid from the selector valve to the ram cylinder and the return flow of the fluid from the ram cylinder to the selector valve so as to actuate the ram, an auxiliary cylinder interposed between the selector valve and the ram cylinder and communicating therewith through one of said pipes leading from the selector valve to one of the end ports so as to be connected in series with the ram cylinder, an auxiliary piston in the auxiliary cylinder operable in accordance with the displacement of the ram, the volume displaced by the auxiliary cylinder being less than that of the ram cylinder, said auxiliary cylinder having associated therewith spaced by-pass ports, each of said by-pass ports being controlled by a non-return valve operable by movement of the auxiliary piston to remove excess fluid from the auxiliary cylinder.

3. A hydraulic remote control apparatus comprising in combination a selector valve connectable to fluid pressure and exhaust, an indicator and a remote hydraulic ram, end ports in said remote hydraulic ram, pipes connecting said end ports to the selector valve, an intermediate port in said hydraulic ram, a pipe connecting said intermediate port with the selector valve, and the indicator comprising a cylinder having end ports connected in one of said pipes connecting the end ports of the remote hydraulic ram with the selector valve, a piston within said cylinder, and a piston rod operatively connecting the piston to said indicator.

CHARLES HYLAND.
